UNITED STATES PATENT OFFICE.

LEWIS J. BAZZONI, OF SWAMPSOFT, MASSACHUSETTS, ASSIGNEE TO UNITED SHOE MACHINERY COMPANY, OF PATERSON, NEW JERSEY, A CORPORATION OF NEW JERSEY.

BLADE-HOLDER.

1,115,048.

Specification of Letters Patent. Patented Oct. 27, 1914.

Application filed May 7, 1909. Serial No. 494,579.

To all whom it may concern:

Be it known that I, LEWIS J. BAZZONI, a citizen of the United States, residing at Swampscott, in the county of Essex and 5 Commonwealth of Massachusetts, have invented certain Improvements in Blade-Holders, of which the following description, in connection with the accompanying drawings, is a specification, like reference characters on the drawings indicating like parts in the several figures.

The present invention relates to devices in which a cutting blade or other tool is removably secured in a handle or support 15 and more particularly it relates to a holder capable of clamping blades of various sizes, such as are commonly employed in cutting out the uppers of boots and shoes.

In this class of devices, it is important 20 to provide means which will clamp the blade securely so that it cannot slip but which may be adjusted easily and quickly for releasing the blade.

Accordingly, a primary object of this invention is to provide a construction of 25 blade holder which shall not only meet these requirements in a more complete and satisfactory manner than is done by existing devices but which shall also be comparatively 30 inexpensive to manufacture.

With this object in view, a principal feature of the invention consists in the provision of blade engaging means and yielding or compensating means, such for example as 35 a spring, for causing the blade engaging means to clamp a blade. By the employment of such means, blades of all sizes within the capacity of the holder are clamped with substantially uniform pressure and 40 there is no liability that the blade will work loose in use, because the blade clamping means adjusts itself automatically to each blade.

A second feature of the invention consists in the provision of novel means for releasing or unclamping the blade. In the preferred embodiment of the invention, this releasing means will be used in combination with the spring or other yielding clamping 45 means hereinbefore mentioned, and it will include two relatively rotatable members, one of which, at least, is provided with a cam surface co-acting with the other member in such a manner that, as the members 50 are relatively rotated by the user of the

holder, the pressure of the spring will be released so that the blade may be adjusted in, or removed from, the handle.

In the illustrated embodiment of the invention, the blade holder comprises; as is usual in this class of devices, a handle or support and a pair of clamping jaws arranged to engage a blade, these jaws being rotatable within the handle and provided with cam surfaces upon their edges to co-act 60 with a part of the handle, as they are drawn inwardly, whereby the jaws are moved toward each other to clamp a blade. Preferably, the part of the handle which co-acts with the jaws comprises a metallic sleeve, 65 secured to the handle, but capable of rotation therein, which sleeve is connected to the rotatable member of the blade releasing means, so that this member will be rotated with the sleeve. In addition to the features 70 above specifically mentioned, the invention comprises also certain other combinations and arrangements of elements, as well as details of construction, which will herein-after be fully described and then defined in 75 the claims.

Referring to the accompanying drawings which illustrate one embodiment of the invention. Figure 1 represents in side elevation a blade holder of the type described 80 with a blade in operative position; Fig. 2 is a central horizontal longitudinal section of the holder shown in Fig. 1 with part of a blade shown clamped within the jaws; Fig. 3 is a similar longitudinal section upon 85 the central vertical plane through Fig. 1; Fig. 4 is a perspective view of the rear portion of the holder with the handle and certain minor parts shown in section; and Fig. 5 is a rear end view of the jaws and associated parts, removed from the handle.

As illustrated, 2 indicates the handle which commonly will be made of wood, fiber, or the like. All of the other parts of the holder will preferably be of metal. As 100 shown in Figs. 2 and 3, the handle is provided with a cylindrical bore 4 into the front end of which is inserted the sleeve 6 provided with a shoulder 8 to bear against the end of the handle 2. In order that this 105 sleeve may be secured in the handle so as to be capable of rotation therein, it is provided that a groove 10, clearly shown in Fig. 4, and one or more pins 12 are driven into the handle so as to lie in the groove. The 110

sleeve is provided with extensions 14 connected with the blade releasing means, as will be explained.

For clamping a blade 16, there is provided a pair of clamping jaws 18 of substantially V-shape in section, each of which at its outer edge is provided with a cam surface 20, co-acting in the usual manner with the walls of a slot formed in the end of the sleeve so that jaws 18 and blade 16 are compelled to rotate with the sleeve.

At their rear ends, as shown in Fig. 5, the jaws are turned outwardly to provide flanges 20' engaging the rear surface of the member 22 of the blade releasing means. This member 22 is provided with recesses 24 to receive the ends of the extensions 14 so that the member 22 will be rotated with the sleeve 6. Extending rearwardly from the member 22 are projections or lugs 26 which coöperate with the other member 28 of the blade releasing means. A spring 30, preferably approximately elliptical in sectional outline, as shown clearly in Fig. 5 is arranged to bear at one end against the edges 32 of the sleeve 6 and at the other against the front surface of the member 22. This spring, therefore, tends constantly to force the jaws rearwardly in the handle and, through the co-operation of the wedge-like inclined or cam surfaces 20 with the walls of the slot in the sleeve, to effect the clamping of blade 16. The member 28 of the blade releasing means is secured rigidly in the handle in any suitable way, as by a pin 34 and its front edge is provided with cam surfaces 36 which engage the lugs 26 of member 22 as the latter is rotated. At their upper ends these cam surfaces may conveniently be provided with stops 38 so that the user can readily know when the lugs 26 in their travel up the inclined or cam surfaces 36 have reached the extreme blade releasing position, at which time the spring 30 will be compressed to its greatest extent. The inclination of the surfaces 36 is preferably such that the force exerted by the spring 30 or any accidental twisting strain given to the blade 16 or jaws 18 will be insufficient to cause the lugs 26 to travel down the surfaces 36. If desired, however, a slight depression to receive the end of lug 26 may be formed in each cam surface 36 just below the stop 38 so that there will be even less liability of accidental release of the blade.

It will be clear that with the lugs 26 at the upper limit of their travel along surfaces 36, the spring 30 will be compressed and the jaws will be free to occupy their most separated position. A blade having been inserted within the jaws, the user will turn the blade and jaws in the handle to cause the lugs 26 to travel down the surfaces 36 until the jaws are forced, through the expansion of spring 30, to clamp the blade. The user

may quickly release the blade at any time by rotating the jaws and blade in the opposite direction to carry the lugs 26 up the surfaces 36.

The jaws 18 are preferably of V-shape in cross section as already stated, the angle between the sides being such that the blade will be engaged simultaneously near its opposite edges by both sides of both jaws and will thus be clamped firmly against twisting or lateral movement.

Instead of, or in addition to, the pins 12, for securing the sleeve 6 in the handle 2 a separate device illustrated in Figs. 1, 2 and 4 may be employed. As shown, a thin plate, such as a leaf spring, 40 provided at its forward end with a projection 42 adapted to enter the groove 10 may be arranged to lie in a shallow recess upon the inside of the handle 2. This plate is provided at its rear end with a tapped hole 44 into which is threaded a screw 46, the head of which is countersunk to be substantially flush with the surface of the handle. By this construction, the screw is located at a portion of the handle where the wall is relatively thick, thus providing ample space within the wall for the screw. If the pins 12 are not used and one or more of such plates 40 are substituted, it will be seen that the sleeve may readily be withdrawn from the handle upon the removal of the screw or screws 46.

While one embodiment of the present invention has been described in detail, it will be understood that the invention is not limited to the details described but may be embodied in various other specific constructions without departing from the spirit and essence of the invention as defined in the following claims.

Having described my invention, what I claim as new and desire to secure by Letters Patent of the United States is:

1. A blade holder comprising a handle, a pair of jaws rotatable therein and provided with cam surfaces constructed and arranged to coöperate with a part of the handle for moving the jaws toward each other to clamp a blade, a spring acting upon said jaws and tending constantly to move them to blade clamping position, in combination with means acting in opposition to said spring to release the blade, the latter means comprising a cam member fixed in said handle and a member rotatable with the jaws and co-acting with the cam member to release the jaws from the pressure of the spring.

2. A blade holder comprising a handle, a pair of jaws constructed and arranged to clamp and hold a blade by frictional engagement only, a spring tending constantly to move said jaws in the direction to clamp a blade and means acting in opposition to the spring to unclamp or release the blade and comprising a cam member and a rela-

- tively rotatable member co-acting therewith, said cam member being fixed in the handle and provided with a stop at the end of the cam surface constructed and arranged to limit the relative movement of said members to less than a complete rotation.
3. A blade holder comprising a handle, a pair of clamping jaws means for moving them toward each other to clamp a blade and means constructed and arranged to release the jaws comprising a cam member fixed in the handle and a rotatable member co-acting therewith but also movable out of contact with the cam member as the blade is clamped.
4. A blade holder comprising a handle, a pair of blade clamping jaws provided with cam surfaces, a sleeve within the handle extending for the greater part of the length of the handle and being constructed and arranged to rotate therein while secured against longitudinal movement, the said sleeve being provided with a surface to coact with the cam surfaces of the jaws, and means for moving the jaws longitudinally of the sleeve including a spring and two co-operating cam members, one fixed in the handle and the other rotatable with the sleeve.
5. A blade holder comprising a handle, a pair of clamping jaws, means for moving the jaws to clamp a blade, a sleeve rotatable within the handle and jaw releasing means acting in opposition to the clamping means including a member fixed in the handle near its rear end and a co-operating member connected with the sleeve to rotate therewith but capable of longitudinal movement relatively thereto.
6. A blade holder comprising a non-metallic hollow handle having walls of decreasing thickness toward its forward end, a pair of clamping jaws, a sleeve rotatable within the handle and co-operating with the

jaws to control their clamping action in combination with means for securing the sleeve against longitudinal movement in the handle comprising a locking member lying between the handle and the sleeve fixed near its rear end to the handle and connected near its front end to the sleeve so as to hold the latter against longitudinal, though permitting rotary, movement with relation to the handle.

7. A blade holder comprising a handle, a pair of similar elongated clamping jaws provided with engaging surfaces substantially V-shape in section constructed and arranged to clamp a thin knife blade upon opposite sides adjacent each edge and provided also with cam surfaces to co-operate with a part of the handle for moving the jaws toward each other, said jaws being provided also with outturned flanges at their rear ends, in combination with a spring engaging the flanges and tending constantly to force the jaws longitudinally relatively to the handle for clamping the blade and means through which the action of the spring may be nullified and the blade released from the jaws.

8. In a blade holder, the combination of a handle 2, a pair of clamping jaws 18, a spring 30 tending to move the jaws into blade clamping position and means wholly inclosed within the handle for actuating the jaws to release the blade comprising a member 28 fixed in the handle and a relatively rotatable cam member 22 movable with the jaws, substantially as described.

In testimony whereof I have signed my name to this specification in the presence of two subscribing witnesses.

LEWIS J. BAZZONI.
